UNITED STATES PATENT OFFICE.

STEPHEN C. RADFORD, OF OSHKOSH, WISCONSIN.

EXCELSIOR.

1,324,066.

Specification of Letters Patent.

Patented Dec. 9, 1919.

Application filed July 28, 1919. Serial No. 313,874.

To all whom it may concern:

Be it known that I, STEPHEN C. RADFORD, a citizen of the United States, and resident of Oshkosh, in the county of Winnebago and State of Wisconsin, have invented new and useful Improvements in Excelsior, of which the following is a description, reference being had to the accompanying drawings, which are a part of this specification.

10 The present invention relates to certain new and useful improvements in wood shavings, more commonly termed excelsior.

One object of the invention is to provide an excelsior shaving so shaped as to fill more space with less material than is necessary with the excelsior now in general use, and to provide an excelsior shaving which will have added strength and increased resiliency.

20 Another object of the invention is to provide an excelsior shaving which will be curved or angular in cross section and which will be coiled in a spiral with the longitudinal extending channel formed by the curvature in the shaving on the inside of the spiral.

With the above and other objects in view which will appear as the description proceeds, my invention resides in the novel construction, combination and arrangement of parts substantially as hereinafter described and more particularly defined by the appended claims, it being understood that such changes in the precise embodiment of the 35 hereindisclosed invention may be made as come within the scope of the claims.

In the accompanying drawing, I have illustrated one complete example of the physical embodiment of my invention, constructed according to the best mode I have so far devised for the practical application of the principles thereof, and in which:

Figure 1 is a perspective view of a portion of a shaving embodying one form of my invention.

Fig. 2 is a transverse sectional view taken through the form of my invention depicted in Fig. 1.

Fig. 3 is a perspective view of a portion 50 of an excelsior shaving embodying a slightly modified form thereof, and

Fig. 4 is a transverse sectional view through the form of my invention depicted in Fig. 3.

Referring now more particularly to Figs. 1 and 2 of the drawing, 5 designates a wood 55 or excelsior shaving which is coiled in a spiral or curled, and has its longitudinally extending side edges 6 on a different plane from its medial longitudinally extending portion 7 to present a curved surface in 60 cross section.

In that form of my invention depicted in Figs. 3 and 4, the shaving 5 has its longitudinally extending side edges 8 also on a different plane from its medial longitudinally extending portion 9. As best shown in Fig. 4, this form of my invention is angular in cross section, whereas that form of my invention depicted in Fig. 2 is curved in cross section.

From the foregoing description taken in connection with the accompanying drawing, it will be readily apparent that I provide a longitudinally channeled excelsior shaving by arranging its side longitudinal edges 75 on a different plane from its medial longitudinally extending portion, which is curved or coiled in a spiral with the channel preferably on the inside of the spiral.

What I claim as my invention is:

1. An article of manufacture consisting of a longitudinally channeled excelsior shaving.

2. An article of manufacture consisting of a longitudinally channeled excelsior shaving coiled in a spiral.

3. An article of manufacture consisting of an excelsior shaving having its side edges on a different plane from its medial longitudinally extending portion in transverse 90 cross section.

4. An article of manufacture consisting of an excelsior shaving having its side longitudinal edges on a different plane from its medial longitudinally extending portion in 95 transverse cross section, said shaving being in the condition of having been coiled in a spiral.

In testimony whereof, I affix my signature.

STEPHEN C. RADFORD.
